COMBINED DOOR KNOB AND ESCUTCHEON

Francis M. Mair, Berkeley, Calif., assignor to Schlage
Lock Company, a corporation

Application April 21, 1958, Serial No. 50,558

Term of patent 14 years

(Cl. D50—3)

FIG. 1

FIG. 2

FIG. 4

Fig. 1 is a perspective view of the combined door knob and escutcheon, showing my new design;
Fig. 2 is a plan view thereof;
Fig. 3 is a side elevational view thereof; and
Fig. 4 is a sectional view taken along line 4—4 of Fig. 2.

I claim:

The ornamental design for a combined door knob and escutcheon, as shown.
